UNITED STATES PATENT OFFICE.

WILLIAM REID, JR., OF GLASGOW, SCOTLAND.

CRANE.

Application filed April 6, 1922. Serial No. 549,976.

To all whom it may concern:

Be it known that I, WILLIAM REID, JR., a subject of the King of Great Britain, residing at Glasgow, in the county of Lanark, 5 Scotland, have invented certain new and useful Improvements in Cranes, of which the following is a full, clear, and exact description, such as will enable others skilled in the art to which it appertains to make and use 10 the same.

This invention has reference to improvements in cranes or similar hoisting mechanism and in some of its aspects it relates more particularly to improvements in and 15 relating to hoisting buckets employed in connection with the hoisting mechanism.

In discharging material by means of a crane from one place to another, for example from a ship's hold to a railway truck or vice 20 versa, it is frequently necessary to raise the full bucket to a greater height than that at which it is required to discharge the bucket; i. e., the bucket must be first raised high enough to clear intervening obstacles, the 25 jib swung round, and the bucket then lowered to a height convenient for tipping.

According to the present invention, means are provided which remain inoperative when the bucket is raised beyond the height for 30 tipping and which, when the bucket is again lowered, actuate the dogs or like locking means when the tipping position is reached.

A further feature and object of the invention resides in the provision of an improved 35 means for turning the hoisting bucket into the required tipping plane.

Other features and objects of the invention will be in part pointed out in connection with the following detailed description and 40 will in part be obvious in connection therewith.

The invention accordingly comprises the features of construction combination of elements, and arrangement of parts, which will 45 be exemplified in the construction hereinafter set forth and the scope of the application of which will be indicated in the claims.

For a complete understanding of the nature and objects of the invention reference 50 is had to the following detailed description and to the accompanying drawings disclosing certain illustrative but preferred embodiments of the invention, and in which—

Figure 1 illustrates a crane jib, suspended 55 crown piece and bucket.

Figure 2 is a view similar to Figure 1 but showing the bucket raised beyond the tipping position.

Figure 3 shows the bucket lowered so as to actuate the locking mechanism.

Figures 4 and 5 are enlarged front and side elevations of the bucket and operating mechanism.

Figures 6 and 7 illustrate to a larger scale 65 sectional elevations at right angles to each other of a preferred construction of crown piece.

Figures 8 and 9 and Figure 10 illustrate 70 modifications.

Referring to the drawings:

A designates the crane jib, B the crown piece and C the bucket. Secured to the latter are two cheeks *a* each having a notch with which engage the lower ends of the arms *b*. Said arms, which constitute locking dogs 75 and normally prevent the bucket tipping, are bifurcated at *c* to enclose the bucket bail or handle D and are each pivotally connected to links *d*. Those links are pivotally secured at their inner ends *d*¹ between the cross straps or plates *e*. *f* are links connected to links *d* and to the upright rod *g* which is provided with a crosshead *g*¹ at its upper end and slotted so as to receive a guiding pin *h* fixed between the said cross straps *e*. *e*¹ are two projecting fixed pins secured to 85 the cross straps and passing through corresponding holes in the cross head and which also serve to guide the latter.

The crown piece is provided at its lower 90 end with two arms *i*, pivoted at *i*¹ and actuated at springs *j*.

The lower ends of said arms are provided with inclined faces *i*² and notches *i*³.

The ropes *k* carrying the crown piece, (see 95 Figures 1, 2 and 3), are secured to a "monkey" or carriage *l* which runs in guides or rails *m*, which latter is provided with holes *m*¹ for the reception of a pin *m*². Thus the downward movement of the crown piece can be limited as desired by inserting the stop pin in the corresponding hole.

In operation the height of the crown piece is adjusted according to the height at which it is desired to tip the bucket. When the full bucket is raised the crosshead *g*¹ co-acts with the inclined faces *i*² thereby forcing the arms *i* apart until it (the crosshead) registers with the notches *i*³. On the further upward movement of the bucket 100 105 110

the crown piece is also raised, as shown in Figure 2, the "monkey" l taking up the slack of the ropes. When over the point where it is desired to deposite its contents, 5 the bucket is lowered, the crownpiece descending with same until its further movement is limited by the stop m^2 acting on the "monkey" l . As the cross head g^1 is temporarily retained within the notches of the 10 arms i the downward movement of the bucket relative to the crown piece results in a relative upward movement of the rod g , which, through links f and d , withdraws the extremities of the arms b from the 15 notches in the cheeks a , thus permitting the bucket to tip under the influence of gravity. On the further downward movement of the bucket the crosshead g^1 by acting on the rounded faces of the notches i^3 forces the 20 arms apart so as to free itself from the crown piece.

Preferably the bucket is of the type in which the axis of the bucket is below the centre of gravity of the bucket when full, 25 but above the centre of gravity when empty so that the bucket, after discharging its contents, automatically rights itself, the bevelled edges of the cheeks a permitting an easy return of the arms b to engage with the notches. 30

After discharging its contents the bucket is again raised, the jib swung round, and the bucket again lowered to be reloaded.

In order to prevent the locking dogs disengaging and engaging with the cheeks a before the bucket has tipped it may be found desirable to retain the locking dogs in the disengaged position for a short interval. 35

This is preferably accomplished by permitting the arms i to make a short vertical movement while retaining the crosshead g^1 , the latter being released at the end of such movement. 40

A preferred construction of such arrangement is illustrated in Figures 8 and 9, which illustrate views at right angles to each other and whereon each arm i is pivotally mounted on a crosshead s secured to guide rods s^1 . Said rods, which are encircled by helical 45 springs s^2 , s^3 and s^4 , are capable of vertical movement within brackets t .

t^1 are bridges held against the brackets t by means of helical springs t^2 encircling bolts t^3 . 50

The action of such arrangement is as follows. Assume the bucket is being lowered and the crown piece has reached the limit of its travel. The crosshead g^1 is then retained by the notched arms i and the locking dogs disengaged. As the bucket continues its downward movement the arms i move in a like direction, the springs s^2 and s^4 being compressed. When the arms i have reached the limit of their downward movement they are forced outwards against the 55

action of the spring pressed bridges t^1 thereby freeing the crosshead g^1 permitting the return movement of the arms i under the action of the springs s^2 and s^4 . The recoil springs s^3 absorb shock on the return of 70 the arms to their normal position. In the slightly modified arrangement shown in Figure 10 the arms i are pivotally carried by crossheads s which slide in slots in brackets t as in the previously described arrangement. 75

The arms i are provided with projecting pins i^5 which slide in guide slots t^4 in the brackets t . The lower ends of said slots are inclined outwardly so that when the 80 pins i^5 move therein they force the arms to the position shown in chain dotted lines thereby releasing the crosshead g^1 . The arms are returned to their normal position by the action of the springs s^5 encircling 85 the fixed guide rods s^6 on which the crosshead s slides.

Slots t^5 permit of the outward movement of the arms i when the latter are forced apart by the crosshead g^1 , the arms thereafter returning to the position shown in full lines under the action of gravity. Or, if desired, the slots t^5 may be shaped so as to slightly compress the recoil springs 95 s^7 during such outward movement, said springs thereby assisting to return the arms to their normal position. 100

In combination with the herein described means for actuating the tip buckets I preferably employ improved means by which the bucket is guided to the desired tipping place before the locking dogs are actuated. Such improved means include preferably a suspended crown piece having a fixed guide, a traveling guide within said crown piece and 105 a member secured at or near the extremity of the usual bucket rope or chain. Said fixed guide comprises a cylinder n which makes a tight fit within the crown piece or is removably secured therein by set screws o^3 and which cylinder is provided with two inverted V shaped slots n^1 . The traveling guide also consists of a cylinder o of such diameter that it is free to move within the crown piece B and this guide is provided 110 with two inverted V shaped slots o^1 and also with two projections o^2 . Normally, said projections rest on a stop ring p secured by screws p^1 within the crown piece. The member q secured to the bucket rope or chain 115 is torpedo shaped and is provided with two projections q^1 . When the bucket is raised the projections q^1 first coat with the sides of the slots o^1 of the traveling guide o . The latter being free to move adjusts itself to 120 said projections q^1 which, when they reach the end of the slots o^1 , raise the traveling guide. The projections o^2 of this guide enter the slots n^1 of the fixed guide and are thereby turned until they enter the 125 130 rectangular slots n^1 .

gular openings at the end of said slots n^1 . In so turning, the moving guide carries the member q round with it and therefore also the bucket, which is then in the required 5 plane.

The crown piece is preferably suspended by two ropes k secured to lugs carried by a ring k^1 held between flanges k^2 and k^3 fixed to the crown piece. The latter may be rotated relative to the ring k^1 and secured by 10 means of pinch screws k^5 , thereby enabling the plane in which the bucket tips to be varied.

By the aforesaid improved guiding means, 15 the member q which preferably consists of two hollow longitudinal sections bolted together, may be made comparatively light so as to enable the workman to readily handle same in transferring the hook of the 20 rope or chain to another bucket.

The link r which is secured to each bucket is provided with an eye which is preferably cut or flattened as at r^1 so that the hook r^2 can be passed over such restricted portion 25 and thereafter prevented from being accidentally disengaged.

A tell-tale or indicator may be provided in the operating cabin to indicate when the bucket is about to tip so that the engine may 30 then be slowed down. Such tell-tale or indicator may be actuated by the "monkey" completing an electric circuit or co-acting with a movable stop before being brought to rest.

Having described my invention what I 35 claim as new and desire to secure by Letters Patent, is—

1. In a crane, in combination, a hoisting bucket, supporting means for said bucket, 40 means for locking said bucket in upright condition, releasing apparatus disposed adjacent the path of said bucket, and suspension means for said releasing apparatus for permitting movement of the latter from its initial position with the rising bucket, without operation of said locking means, 45 said releasing apparatus becoming operative to trip said locking means at said initial position upon descent of said bucket, said releasing apparatus including a pair of spring pressed arms cooperable with said locking means.

2. In a crane, in combination, a hoisting bucket, supporting means for said bucket, 55 means for locking said bucket in upright condition, releasing apparatus disposed adjacent the path of said bucket, a flexible suspension member for said releasing apparatus permitting movement of the latter with the rising bucket, and a counter weight for taking up slack of said flexible member when said releasing apparatus is being raised by said bucket.

3. In a crane, in combination, a hoisting bucket, supporting means for said bucket,

means for locking said bucket in upright condition, releasing apparatus disposed adjacent the path of said bucket, a flexible suspension member for said releasing apparatus permitting movement of the latter with the 70 rising bucket, a counter weight for taking up slack of said flexible member when said releasing apparatus is being raised by said bucket, a guideway for said counter weight, and an adjustable stop for limiting movement of said counter weight. 75

4. In a crane, in combination, a hoisting bucket, supporting means for said bucket, means for locking said bucket in upright condition releasing apparatus disposed adjacent the path of said bucket, and suspension means for said releasing apparatus for permitting movement of the latter from its initial position with the rising bucket, without operation of said locking means, said 80 releasing apparatus becoming operative to trip said locking means at said initial position upon descent of said bucket.

5. In a crane, in combination, a hoisting bucket, supporting means for said bucket, 85 means for locking said bucket in upright condition, releasing apparatus disposed adjacent the path of said bucket, a flexible suspension member for said releasing apparatus permitting movement of the latter with the rising bucket, and a counterweight for taking up slack of said flexible member when said releasing apparatus is being raised by 90 said bucket, said releasing apparatus including a pair of spring pressed arms cooperable with said locking means.

6. In a crane, in combination, a hoisting bucket, supporting means for said bucket, means for locking said bucket in upright condition, releasing apparatus disposed adjacent the path of said bucket, and suspension means for said releasing apparatus for permitting movement of the latter from its initial position with the rising bucket, without operation of said locking means, said 100 releasing apparatus becoming operative to trip said locking means at said initial position upon descent of said bucket, said releasing apparatus including a pair of cooperating arms cooperable with said locking means and being mounted for pivotal and translatory movement. 105

7. In a crane, in combination, a jib, a bucket, supporting means therefor carried by said jib, means for locking said bucket in upright condition and means carried by said jib for releasing said locking means comprising a member relatively movable in respect to said bucket having jaws adapted to automatically and yieldingly engage a part of said locking means when the bucket is being elevated. 110

8. In a crane, in combination, a jib, a bucket, supporting means therefor carried by said jib, means for locking said bucket in 115

upright condition, means for releasing said locking means comprising a member suspended from said jib and relatively movable in respect to said bucket, said member having 5 jaws pivotally connected thereto adapted automatically to engage a part of said locking means upon elevation of said bucket.

9. In a crane, in combination, a jib, a bucket, supporting means therefor carried 10 by said jib, means for locking said bucket in upright condition, means for releasing said locking means comprising a member suspended from said jib having jaws slidably and angularly movable thereon adapted 15 resiliently to engage a part of said locking means.

10. In a crane, in combination, a jib, a bucket, supporting means therefor carried 20 by said jib, means for locking said bucket in upright condition, means for releasing said locking means comprising a member suspended from said jib and relatively movable in respect to said bucket, said member having jaws slidably and angularly movable 25 thereon adapted resiliently to engage a part of said locking means, and a guide for said jaws.

11. In a crane, in combination, a jib, a bucket, supporting means therefor carried 30 by said jib and releasable means for locking said bucket in upright condition including dogs connected to said supporting means adapted to be engaged by parts of said bucket and movable to be disengaged there- 35 from, said engaging parts having camming surfaces adapted to assist reengagement of said dogs.

12. In a crane, in combination, a jib, a bracket, elevatable supporting means there- 40 for carried by said jib and a guide member carried by said jib and cooperable with the bucket upon elevation thereof for automatically rotating said bucket on its vertical axis into a predetermined vertical plane, 45 including an auxiliary member carried by and rotatable on said guide member adapted to cooperate with a part of said bracket supporting means.

13. In a crane, in combination, a jib, a bucket, elevatable supporting means there- 50 for carried by said jib and a guide member carried by said jib and cooperable with the bucket upon elevation thereof for automatically rotating said bucket on its vertical axis 55 into a predetermined vertical plane, includ- ing an auxiliary member carried by and rotatable on said guide member adapted to cooperate with a part of said bucket supporting means to move the same into a fixed ro- 60 tative relationship therewith.

14. In a crane, in combination, a jib, a bucket, elevatable supporting means there- 65 for carried by said jib and a guide member carried by said jib and cooperable with the bucket upon elevation thereof for automatici-

cally rotating said bucket on its vertical axis into a predetermined vertical plane, including an auxiliary member adapted to be longitudinally moved by said bucket supporting means on said guide member 70 and to be moved by the latter to a predetermined rotative relationship therewith.

15. In a crane, in combination, a jib, a bucket, elevatable supporting means there- 75 for carried by said jib and a guide member carried by said jib and cooperable with the bucket upon elevation thereof for automatically rotating said bucket on its vertical axis into a predetermined vertical plane comprising a rotatably adjustable cylindrical member, a second cylindrical member carried thereby slidably and rotatable in respect thereto, and a third cylindrical member fixed to said first mentioned member in adjustable rotative relationship thereto, and cooperative with said second member to rotate the same into a predetermined rotative relationship thereto, said second member being cooperative with a part of said bucket suspending means to rotate the same into a 80 predetermined rotative relationship therewith.

16. In a crane, in combination, a jib, a bucket, elevatable supporting means there- 85 for carried by said jib and a guide member carried by said jib and cooperable with the bucket upon elevation thereof for automatically rotating said bucket on its vertical axis into a predetermined vertical plane, said guide member comprising a cylindrical 90 member, a second cylindrical member carried thereby, slidably and rotatable in respect thereto, said members having inclined slots adapted to receive parts of said bucket suspending means, and a third cylindrical 95 member fixed to said first member and having an inclined lower face adapted to cooperate with projecting parts of said second member.

17. In a crane, in combination, a jib, a bucket, elevatable supporting means there- 100 for carried by said jib, means for locking said bucket in upright condition and a guide member cooperable with the bucket upon elevation thereof for rotating said bucket 105 into a predetermined vertical plane having parts automatically engageable with cooper- 110 ating parts of said locking means, and op- erative to release said locking means to permit tipping of said bucket.

18. In a crane, in combination, a jib, a bucket, elevatable supporting means there- 115 for carried by said jib, means for locking said bucket in upright condition and a guide cooperable with the bucket upon ele- 120 vation thereof for rotating said bucket into a predetermined vertical plane having parts adapted to engage cooperating parts of said locking means upon contact therewith, and automatically operative to release said lock- 125

ing means upon movement of said bucket tending to break said contact.

19. In a crane, in combination, a jib, a bucket, elevatable supporting means therefor carried by said jib, means for locking said bucket in upright condition and a guide member for rotating said bucket into a pre-determined vertical plane having parts

adapted detachably and resiliently to engage cooperating parts of said locking means for movement thereof in respect to said bucket thereby to release said locking means to permit tipping of said bucket.

In testimony whereof I affix my signature.

WILLIAM REID, JR.
